(57) **CLAIM**

The ornamental design for a modular corner stair set, as shown and described.

DESCRIPTION

FIG. 1 is a front, top perspective view of a modular corner stair set, showing my new design, to include four components configuration in FIGS. 1-8;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded perspective view from the front, top of the modular corner stair set of FIG. 1, showing one component separated to reveal aspects of the design that may not be apparent in other views; and,

FIG. 10 is an exploded perspective view of the modular corner stair set, showing all the components separated to reveal aspects of the design that may not be apparent in other views.

The claim is directed to the collective appearance of the modular corner stair set components arranged as shown in the figures.
